ARTICLE FOR NECKWEAR

Waldo H. Logan, Chicago, Ill.

Application September 26, 1942, Serial No. 459,799

1 Claim. (Cl. 2—150)

My invention relates in general to wearing apparel and has more particular reference to neckwear, the invention pertaining specifically to so-called four-in-hand neckties.

For the sake of neatness, four-in-hand neckties are ordinarily tightly knotted, and consequently such ties are subject to appreciable wear in the knotted portions thereof. Ordinarily fraying of the necktie occurs first in such portions. Since the knot of a four-in-hand tie is ordinarily disposed immediately beneath the chin of the wearer, ties of the character mentioned rapidly become soiled at the knot through contact with the wearer's chin. As soon as a necktie thus becomes soiled or frayed, due to wear at the knot, it is ordinarily thrown away as having outlived its usefulness; and it is an important object of my present invention to extend the useful service life of neckties by preventing soilage and wear and for concealing wear and soilage in order thus to make attractively wearable and useful worn or soiled neckties which otherwise would be discarded.

An important object of the present invention is to provide a cover or bib adapted for application to a four-in-hand tie, after the same has been knotted, in order to cover the knot; a further object being to provide a bib of inexpensive character which may be readily applied and which, when in place, will appear to be a part of the tie itself.

Another important object is to form the bib of material, patterned or colored to afford a pleasing contrast with the material of the tie with which it is used, the bib serving not only to protect the knotted portions of the tie against soilage, but also to enhance the decorative effect of the tie by virtue of the blending or contrasting color or pattern selected in the bib and the tie with which the same is used.

Another important object is to provide several tie bibs of contrasting pattern or color, or both, adapted to be merchandised as a bib set as such or in combination with a particular necktie so that by using one or other of the bibs with the tie, a number of pleasing neckwear effects may be created.

Another important object of the invention is to provide a fabric tie bib comprising a tapered, sleeve-like body adapted to snugly receive the tapered knot of a four-in-hand tie, the body being formed with a flap at its larger end in position to wrappingly enclose the top of the knot; a further object being to provide a flap of size and shape adapted for tucking into the bib body at

the back of the enclosed knot to thereby secure the bib on the knot by virtue of the tucked-in flap.

Still another important object is to provide an elastic bib body adapted to contract upon and snugly embrace a four-in-hand tie knot whereby the bib is adapted to fit a knot of any size within the limits normally encountered in neckwear of the character mentioned.

A still further important object is to form the sleeve-like body portion of the bib with a panel of elastic material whereby to contract the bib body snugly upon a tie knot, the panel preferably being located in the side of the bib body remote from the tuck-in flap so that said elastic panel, when the bib is in place upon the knot of a necktie, will be disposed in concealed position facing rearwardly of the knot.

These and numerous other important objects, advantages, and inherent functions of the invention will be fully understood from the following description, which, taken in connection with the accompanying drawing, discloses a preferred embodiment of the invention.

Referring to the drawing:

Figure 1 illustrates a bib embodying the present invention as applied to the knot of a four-in-hand tie which is shown in position fitted upon a conventional collar.

Figure 2 is a sectional view taken substantially along the line 2—2 in Figure 1.

Figure 3 is a perspective view of the bib;

Figure 4 is a sectional view taken substantially along the line 4—4 in Figure 3; and

Figure 5 is a fragmentary view of the bib.

To illustrate my invention I have shown on the drawing a four-in-hand necktie fitted to a conventional collar 11, the necktie having a central portion 13 extending within the folded collar, a knot 15 disposed at the front of the collar and having the downwardly tapered, conventional four-in-hand knot shape, the ends 17 and 19 of the tie extending through and being dependent from the lower end of the knot.

As heretofore mentioned, the knot 15, being disposed immediately beneath the chin of the wearer, is apt to become soiled through contact with the wearer's chin more rapidly than the remaining portions of the necktie. Furthermore, since a four-in-hand tie, for the sake of neatness, is tightly knotted, fraying and wear ordinarily first occur at the knotted portions, and the tie may be rendered unwearable through fraying and soilage at the knot while the larger, decorative

portion of the tie, namely, the large end 19, remains in useful, wearable condition.

In order to extend the useful life of neckties of the four-in-hand variety embodying a downwardly tapering knot 15, I provide a knot cover or bib 21 comprising fabric material formed to provide a tapered sleeve-like body portion 23 and a tucking flap 25. The bib may be applied to the necktie after the formation of the knot 15 by inserting the tie ends 17 and 19 through the sleeve-like body 23 and sliding the bib upwardly until the knot 15 is received therein. The tucking flap 25 is mounted on the bib body 23 at the upper, or larger, end thereof in position to be curled rearwardly over the top of the knot 15, the flap 25 being sufficiently long to enable the end thereof to be tucked into the sleeve-like body 23 at the back of the knot and thereby held in place.

It will be noted that the opposite side edges of the flap 25 adjacent the body are cut away as at 27 to receive the knot connected ends of the neck encircling tie portion 13; and the flap may be tapered from its widest portion 29 toward the flap tucking end thereof to facilitate tucking operation while at the same time disposing said widest portion 29 at the top of the tie knot 15.

In order that the sleeve-like knot enclosing body 23 may snugly embrace the tie knot 15 when in place thereon, said body 23 is preferably of elastic construction so that the same may conform to the shape of the tie knot. To this end, the bib may comprise a piece of fabric including a body forming portion 33 having opposite side edges 35 converging inwardly toward the lower edge of the fabric piece, the tucking flap 25 being connected to the body forming portion 33 substantially centrally and at the upper edge of the body forming portion 33.

The body forming portion 33 is curved to the desired tapered, sleeve-like form by bringing the edges 35 into spaced apart relationship, and said edges are connected together by any suitable elastic means forming a panel 37 between and interconnecting said spaced edges 35. The elastic means forming the connecting panel 37 may comprise any suitable knitted, netted, woven or other elastic fabric secured in any preferred fashion between the edges 35, as shown so as to constitute the fabric portion 33 and the elastic panel 37, as an elastic or stretchable sheath adapted to contract upon and conform to the shape of the tie knot to which it is applied.

As shown more particularly in Figure 4 of the drawing, the panel 37 preferably comprises a woven elastic strip secured at its edges, as by stitching 39 to the opposed edges 35 of the panel forming portion 33, the stitched edges of the panel portion 37 being inter-folded with the edges 35 in forming the stitched seams whereby to prevent raveling of said edges. The upper and lower edges of the bib body 23 and the marginal edges of the tucking flap 25 also may be folded and stitched, as at 41, to provide non-raveling edge beads.

The body member, therefore, provides a protecting sheath in the form of an inverted frustum cone, but hollow, with an extending tongue-like

flap at the front thereof. The hollow cone-shaped part extends over the tie to cover the tie knot, and the flap extends over the upper edge of the knot and is then tucked in between the rear inner side of the tubular member and the back of the tie knot, as clearly shown in Fig. 2.

If desired, of course, the tucking flap 25 may be formed as a piece separate from the portion 33 and secured thereto, as indicated in dotted lines at 43, the base of the flap, in that event, being secured to the inner surface of the body forming portion 33, the upper edge of which will extend in front of the base of the flap when the bib is in mounted position on the tie knot.

The protecting bibs or sheaths may be made in sets of contrasting colors, or they may be made of differently patterned materials, or both. A number of bibs may be merchandised either as a set, to be retailed as such, or each bib may be sold individually, or may be merchandised in combination with a particular necktie; and where a bib is worn on a necktie of contrasting color or pattern, it affords an attractive adjunct for the creation of pleasing and novel neckwear combinations. Different protecting sheaths or bibs, of course, may be worn successively on the same tie, or they may be worn successively on different ties, thereby affording a wide range of sartorial effects at minimum expense, and employing a minimum number of neckties and sheaths or bibs.

While the primary purpose of the present invention is to afford means for producing a wide variety of pleasing neckwear combinations, the bibs do also protect the tie knot against soilage and conceal the effects of wear at the tie knot, thereby materially increasing the effective service life of the tie itself.

It is thought that the invention and its numerous attendant advantages will be fully understood from the foregoing description, and it is obvious that numerous changes may be made in the form, construction and arrangement of the several parts without departing from the spirit or scope of the invention, or sacrificing any of its attendant advantages, the form herein disclosed being a preferred embodiment for the purpose of illustrating the invention.

The invention is hereby claimed as follows:

A tie knot shield comprising a piece of fabric and a strip of elastic material extending between and secured to the opposite side edges of said piece of fabric and holding the same in yieldingly spaced relationship, substantially throughout the length of said side edges, thereby forming a tubular, tapered and resiliently contractile sheath for receiving and snugly hugging a tie knot, and resiliently conforming to its shape, said piece of fabric having a tucking tab at and extending from its top edge in position, at the top of the sheath, diametrically opposite said strip of elastic material, said tab being adapted to embrace the top of a tie knot in the sheath, and having an end tuckable between the strip of elastic material and the tie knot, in position to be gripped and held in place against the knot by said strip.

WALDO H. LOGAN.
